FLAT WRAPPING MACHINE

Raymond E. Ackley, Chicago, Ill., assignor to
R. R. Donnelley & Sons Co., Chicago, Ill., a corporation of Illinois

Application July 16, 1932, Serial No. 622,935

24 Claims.

(Cl. 93—2)

My invention relates more particularly to machines for wrapping articles, and particularly books, in flat condition and my primary object, generally stated, is to provide improvements in machines of this general character whereby they will be caused to function to better advantage.

Certain of my more specific objects are to provide improvements to the end that the books supplied to a hopper will be positively fed therefrom and without ruffling of the pages thereof; to provide simple and effective means whereby the machine will be adapted for the feeding, from the hopper, of articles of widely varying thicknesses; to provide for the depositing of the articles on the wrappers in such a way as to insure the proper positioning of the articles relative thereto and without displacement of the wrappers; to provide improvements in the means for holding the articles and wrappers against displacement in the feeding operation and while being operated on as for example by the folding devices; to provide improved means for insuring the proper adhesion of the wrappers, folded about the articles, at the glued joints thereof; to provide in a machine involving an endless conveyor having projections which advance the articles and wrappers and means which move the wrapped articles beyond the projections, improvements in the means last referred to for insuring against damage to the wrapped articles by the projections in the movement thereof out of the feeding plane; and to provide for the novel folding of the wrappers about the articles and the location of the lines of adhesion of the free edges of the wrappers to the portions thereof which these free edges overlie.

Referring to the accompanying drawings:

Figure 1 is a view in side elevation of one end, the entering end, of a wrapping machine embodying my invention.

Figure 2 is a similar view of the middle portion of the machine.

Figure 3 is a similar view of the other end, of the machine.

Figure 4 is a plan view of the portion of the machine shown in Fig. 1.

Figure 5 is a plan view of the portion of the machine shown in Fig. 2.

Figure 6 is a plan view of the portion of the machine shown in Fig. 3.

Figure 7 is an enlarged fragmentary section taken at the line 7—7 on Fig. 6 and viewed in the direction of the arrows.

Figure 8 is a similar view taken at the line 8—8 on Fig. 6 and viewed in the direction of the arrows.

Figure 9 is a similar view taken at the line 9—9 on Fig. 6 and viewed in the direction of the arrows.

Figure 10 is an enlarged broken longitudinal sectional view of the portion of the machine shown in Figs. 1 and 4, the section being taken at the

irregular line 10—10 on Fig. 4 and viewed in the direction of the arrows.

Figure 11 is a similar view, the section being taken at the line 11 on Fig. 4 and viewed in the direction of the arrow.

Figure 12 is an enlarged sectional view of the machine, the section being taken at the line 12—12 on Fig. 5 and viewed in the direction of the arrows.

Figure 13 is a section taken at the line 13—13 on Fig. 5 and viewed in the direction of the arrows.

Figure 14 is a section taken at the line 14—14 on Fig. 6 and viewed in the direction of the arrows.

Figure 15 is a section taken at the line 15—15 on Fig. 6 and viewed in the direction of the arrows.

Figure 16 is a section taken at the line 16—16 on Fig. 6 and viewed in the direction of the arrows.

Figure 17 is an enlarged section taken at the line 17—17 on Fig. 1 and viewed in the direction of the arrows.

Figure 18 is a view in side elevation, but of reduced size, of the mechanism shown in Fig. 16.

Figure 19 is a perspective view of the wrapped book.

Figure 20 is a plan view of a portion of the machine of the preceding figures showing it as equipped with members over which the wrappers are folded, the machine being shown as stripped of all of the parts thereof other than those which directly cooperate with the members referred to; and

Figure 21, a view like Fig. 15 showing the members referred to in Fig. 20, in place.

As a preface to the following description of the illustrated machine it may be stated it is of the type involving the feeding of wrappers and books, the latter to superposed position on the wrappers, and the moving of the assembled wrappers and books into position for the folding of the wrappers about the books and the securing of the wrappers in position.

Referring to the details of the illustrated machine as shown in Figs. 1—18, inclusive, the machine comprises, generally stated, an endless conveyor 30 which extends lengthwise of the machine substantially throughout the length of the latter; wrapper-feeding mechanism 31 at the entering end of the machine; an endless wrapper-conveyor 32 paralleling the conveyor 30 and conveying the wrappers to a position in which the conveyor 30 engages them; a hopper 33 for the books and from which the latter are fed by the conveyor 30 to superposed position on the wrappers, the conveyor 30 thereafter advancing the assembled books and wrappers; means 34 for folding the narrow edge portion of the wrapper about the book; means 35 for folding the wide edge portion of the wrapper across the top of the book; means 36 for holding the book and wrapper, while moving and operated on by the means 34 and 35.

60 60

from being disarranged; means 37 for applying an adhesive, such as glue, to the underside of the part of the wrapper which extends below the book; means 38 for folding the free edge of the portion which extends over the top of the book around the underside of the book; means 39 for pressing the wrapped book at the portion thereof to which the adhesive is applied to insure proper adherence; means 40 for holding the book and wrapper 10 from becoming disarranged while the means 37, 38 and 39 are operating; and means 41 for advancing the wrapped book relative to the conveyor 30 to insure proper disengagement from the wrapped book of the portions of the conveyor 30 15 by which the wrapped book is fed.

Referring to the conveyor 30 it is shown as in the form of a sprocket chain 42 mounted at its opposite ends on sprockets 42^a and 42^b journaled on the stationary frame 43 of the machine, the 20 chain being provided at intervals therealong with pairs of outwardly extending fingers 44, the fingers of each pair being spaced apart crosswise of the chain as shown in Fig. 17.

The frame of the machine presents an upper 25 bed portion formed at the entering end thereof of parallel bars 45 spaced apart and extending lengthwise of the machine and beyond these bars, in part, of plates, this bed being slotted lengthwise of the machine throughout the length of the conveyors 30 and 32 to permit the fingers 44 on the upper straight reach of the chain 42 and studs, hereinafter referred to, on the conveyor 32, to extend upwardly above the plane of the bed.

The conveyor 30 is driven by the main drive 30 shaft 46 journaled on the frame of the machine and shown as driven by a motor 47 having sprocket-chain connection 48 with a shaft 49 connected with the drive shaft 46 by speed-reducing mechanism indicated at 50. The drive from the 40 drive shaft 46 to the conveyor 30 is through a helical gear 51 on the shaft 46 meshing with a helical gear 52 on a vertical shaft 53 rotatably mounted on the machine-frame, the shaft 53 being provided at its upper end with a helical gear 54 meshing with a second helical gear 55 rigid with a shaft 56 journaled on the machine-frame and to which the sprocket 42^b is secured.

The sheet conveyor 32 comprises a pair of sprocket chains 57 located at opposite sides of the 50 conveyor 30 and each provided with a series of studs 58 hereinbefore referred to and extending outwardly therefrom and spaced apart the same distances as the fingers 44. The chains 57 are mounted at their ends on sprockets 59 and 60 carried by shafts 61 and 62, respectively, journaled on the frame of the machine in such position that the upper reaches of the chains 57 extend in substantially the same horizontal plane as the upper reach of the chain 42, the chains 57 being driven 60 in the same direction and at the same speed as the chain 42.

The chains 57 are driven by the drive shaft 46 through a bevel gear 46^a on the drive shaft 46 meshing with a bevel gear 63 on a jack-shaft 64 journaled on the machine frame and carrying a sprocket 65 connected by a sprocket-chain 66 with a sprocket 67 fixed to the shaft 61.

The feeding mechanism 31 (Figs. 1, 4 and 10) 70 for the wrappers represented at 68 and which may be sheets of paper suitable for wrapping the books and which operates to feed the wrappers, in succession, from a pile thereof, to the wrapper-conveyor 31, is of common and well known construction and therefore a general description thereof will suffice. This mechanism comprises a hopper

69, to receive the pile of wrappers, located at the entering end of the machine and above feed rolls 70 mounted on a shaft 71 driven by a sprocket chain 72 connected with sprockets 73 and 74 on the shafts 71 and 64, respectively. Located adjacent the bottom of the hopper 69 which is open at its discharge end are suction devices one of which is shown at 75 mounted to be raised into engagement with the lowermost wrapper and lowered to draw the edge of the wrapper into engagement with the rolls 70, by mechanism driven by a cam 76 on the shaft 71.

This feeder mechanism also comprises means operating to press the wrapper against the rolls 70 to insure the feeding of the wrapper to the conveyor 32, these means comprising a roller 77 mounted on a lever 78 fulcrumed between its ends 79 on an arm 80 extending from a rock member 81 actuated from the shaft 71 (by means not shown), a spring 82 yieldingly forcing the 20 rollers 77 toward the rolls 70. A separating and lifting member 83 mounted to rock at 84 and operated by the shaft 71 serves to prevent the drawing down of more than one wrapper at a time by the suction means referred to and exerts 25 a lifting force on the wrappers above it to facilitate the feeding of the lower wrapper.

The wrapper-feeding mechanism described operates to feed the wrappers one at a time to the bed of the machine and between stationary 30 guides 85 thereon, into a position to be engaged at their rear edges by the studs 58 as the latter move up to the upper reach of the chains 57.

The hopper 33 for the books represented at 86, (Figs. 1, 4, 11 and 17) comprises a bottom 35 plate 87 slotted longitudinally of the machine as represented at 88 to receive the fingers 44, side-plates 89 secured to the bottom 87, a front plate 90 reaching short of the bottom of the hopper, rods 91 extending along the sides of the 40 plates 89 and connected therewith by clamp-brackets 92 on rods 93 projecting outwardly from these plates, a rod 94 extending along the face of the front plate 90 and secured thereto by brackets 95 on which the plate 90 is vertically 45 adjustable, in accordance with common practice, and to the ends of the rods 91 by clamp brackets 96, and a bar 97 having extensions 98 at its ends to which the rods 91 are connected.

The hopper structure described is supported 50 for vertical adjustment on the lower ends of threaded shafts 99 having screw-threaded engagement with the extensions 98, which latter slide on vertical posts 100 rigidly secured to, and rising from, the frame of the machine. The 55 shafts 99 are rotatably mounted in heads 101 secured to the upper ends of the posts 100 and are provided with worm wheels 102 which mesh with worms 103 secured to a shaft 104 journaled in the heads 99 and extending crosswise of the 60 machine. By means of a handle 105 on the shaft 104 the latter may be rotated to bodily raise or lower the hopper, as desired, relative to the conveyor 30, depending on the direction in which this shaft is rotated.

Hinged as represented at 106, to the edge of the hopper bottom 87 at the delivery side of the hopper are bars 107, shown as three in number, located side by side and spaced apart with the spaces therebetween in longitudinal alignment 70 with the slots in the hopper 33, the bars 107, which form an extension of the hopper bottom 87, sloping toward the conveyors 30 and 32. The free ends of the two outer ones of the bars 107 are held in spaced relation to the conveyor 30 75

and the wrappers thereon as by means of rods 107^a shown as extending through the guides 108 and secured at their upper ends to a cross bar 107^b rotatable in clamp brackets 107^c vertically 5 adjustable on posts 107^d rising from the frame of the machine at points laterally beyond the wrappers. The free end of the central one of the bars 107 is shown as provided with a roller 107^e at which it rests on the conveyor 30 beneath it, the wrappers traveling under this roller. The bars 107 thus form a slideway along which the books, as they are conveyed from the hopper 33, travel in a downwardly inclined path to superposed position on the wrappers, the bars 107, by 10 being hinged to the hopper, automatically adjusting themselves in the adjusting of the hopper 33 vertically.

The fingers 44 in the operation of the conveyor 30 engage the rear edge of the lowermost book 20 in the hopper 33 forcing it out of the latter and onto the hopper-bottom-extension 107 and between guide rails 108 carried by the two outside ones of the bars 107, the conveyor 30 in its continuing movement pushing the book from the hopper-bottom-extension 107 whereupon the book comes lightly to rest on the wrapper beneath it. Following the operation just described the stud 58 by which the wrapper just referred to has been moved along the machine, moves, in the 25 movement of the chains 57 around the sprockets 60, out of engagement with the wrapper, whereupon the wrapper and the book thereon are advanced solely by the conveyor 30.

As shown the book-hopper is located to one 35 side of the center line of the machine so that the books are fed to such a position on the wrappers that the wrappers at one edge of the books extend therebeyond a short distance and at the other edge a relatively great distance, 40 these extending portions of the wrapper being represented at 109 and 110, respectively.

The means 34 for folding the narrow extending portions 109 of the wrappers about the books comprise a flare device formed of a stationary 45 plate 111 which extends at one end, 112, below the plane of the wrapper portion 109 and gradually curves upwardly and inwardly, in accordance with common practice, into substantially horizontal position directly above the book, as 50 shown in Fig. 13.

The folding means 35 for the wide extension portion 110 of the wrapper comprises a wire 113 supported on a post 114 rising from the machine frame, one end 115 of the wire 113 extending beneath the wrapper portion 110. From this end the wire curves upwardly and inwardly as represented at 116 alongside of the holding means 36 and beyond these means inwardly and downwardly as shown at 117. Adjacent to, and below, 60 the portion 116 of the wire 113 is a flare device 118 in the form of a plate one end 119 of which extends below the wrapper portion 110 and gradually curves upwardly and inwardly to a position in which its other end 120 extends directly over the book.

It will be manifest from the foregoing that as the wrapper moves over the guide wire 113 its wide portion 110 will be folded upwardly and inwardly around the adjacent edge of the book, the flare device 118 operating close to the edge of the book folding the wrapper around this edge and over the top of the book and the terminal portion 117 of this wire insuring the flat positioning of the wrapper over the top of the book as shown in Fig. 14.

The holding means 36 for the books and wrappers comprises an endless chain 121 trained over sprockets 122 and 123 rotatably mounted in a frame 124 supported, to be vertically adjustable in any desirable way, on a standard 125 rising 5 from the frame of the machine, the chain 121 being provided at intervals along its length with outwardly extending pairs of lugs 126 spaced apart and equipped with rubber rolls 127 through which pins 128 loosely extend. Beyond each roll 127 10 is a cross pin 129 on the lugs 126 and extending laterally beyond the chain 121 and adapted to ride on a ledge 130 secured to the frame 124.

The chain 121 is driven at the same surface speed as the conveyors 30 and 32 as by a sprocket 15 chain 131 trained over a sprocket 132 rigidly connected with the sprocket 122, and a sprocket 133 connected with a shaft 134 driven as through a pair of helical gears (not shown) by a shaft (not shown) having sprocket chain connection 135 with 20 the drive shaft 46.

In practice the frame 124 would be adjusted vertically to a position, depending on the thickness of the books to be wrapped, in which, as the books pass beneath the lower reach of the chain 121 25 25 the rolls 127 will be forced upwardly against the pins 129 and therefore have no tendency to roll. The rolls 127 thus form a series of book-contacting surfaces a plurality of which simultaneously press against the book effecting a much more 30 secure holding of the book and wrapper against displacement than in the case of a construction having a continuous line bearing on the book as in the case of a chain directly engaging the book.

The gluing mechanism 37 which is engaged by 35 the wrapper after the latter has been folded about the book by the folding means 34 and 35 and as shown in Fig. 14, comprises a glue wheel 136 mounted on a shaft 137 to engage the portion of the wrapper which extends beneath the book adjacent the edge of the latter over which the wrapper portion 109 is folded and apply a line of glue thereto, the wheel 136 extending into a body of glue in a pot thereof represented at 138.

The drive for the shaft 137 comprises a bevel 45 gear 139 on the shaft 137 and meshing with a bevel gear 140 on a jack shaft 141, and a sprocket chain connection 142 between the shaft 141 and the drive shaft 46.

The folding means 38 comprise a plate 143 one 50 end of which and represented at 144 extends horizontally over the part of the wide wrapper portion 110 which extends beyond the book (Fig. 7), this plate curving downwardly and inwardly as represented in Figs. 8, 9 and 15 into a position in which 55 it extends substantially horizontally directly below the book thereby folding the wrapper into the final position shown in Fig. 16 this free edge of the wrapper becoming adhered to the strip of glue represented at 145 applied, to the underside of 60 the wrapper which extends across the bottom of the book, by the gluing mechanism as above explained.

Referring now to the presser mechanism 39 which is provided to insure the adhering of the 65 free edge of the wrapper to the glue, it comprises the following described mechanism:

Journalized on a stationary bracket 146 is a shaft 147 provided at one end with a gear 148 and at its opposite end with a sprocket 149, this sprocket 70 extending upwardly into a position to be driven at its teeth by the pins which connect together the links of the feed conveyor 39. The gear 148 meshes with a pinion 150 journalized on the bracket 146 and meshing with a pinion 151 also journalized 75

on the bracket 146 and connected with a roller 152 located below the wrapped book at its glued edge (Fig. 16).

Pivoted at 153 on the bracket 146 is an arm 154 carrying a roller 155 positioned directly above the roller 152 and adapted to bear against the upper surface of the wrapped book, the roller 155 being connected with a pinion 156. The roller 155 is driven from the gear 151 through the medium of meshing gears 157 and 158 which, respectively, mesh with the gears 151 and 156. The gears 157 and 158 are rotatably mounted on a bar 159 pivotally connected at its upper and lower ends with the arm 154 and the bracket 146, respectively, through the medium of links 160 and 161. A coil spring 162, connected at its opposite ends with studs 163 and 164 on the bracket 146 and the arm 154, respectively, operates to force the roller 155 with yielding pressure toward the roller 152 to exert the desired rolling clamping pressure upon the glued edge of the wrapped book. The arm 154 is shown as provided with a screw device 165 having threaded engagement with the arm 154 for lengthwise adjustment and adapted to bear at its lower end against the bracket 146, thereby permitting the operator to vary the degree of clamping pressure exerted by the rollers.

The mechanism 40 for pressing down on the book to hold it and the wrapper against accidental displacement while the mechanisms 37, 38 and 39 are operating, is of the same construction as the mechanism 36 above described, its frame portion represented at 166 and which is supported on the frame of the machine to be vertically adjustable, being provided with sprockets 167 and 168 over which the endless sprocket chain 169 provided with spaced apart book-contacting members 170 as explained of the mechanism 36, is trained. The drive of the chain 169 is through a sprocket chain 171 trained over a sprocket 172 operatively connected with the sprocket 168 to rotate therewith and a sprocket 173 secured to a shaft 174 driven, as through the medium of a pair of helical gears (not shown) by a sprocket 175 connected by a sprocket chain 176 with a sprocket on the drive shaft 46.

The mechanism 41 for engaging the wrapped books to advance them away from the fingers 44 by which they are conveyed as above described, comprises an endless chain 177 trained over sprockets 178 and 179 rotatably mounted in a frame 180 supported at a side thereof on the frame of the machine. The chain 177 which extends in longitudinal alignment with the conveyor 30 is provided at intervals with outwardly extending lugs 181 which are adapted in the operation of the machine to pass between the fingers 44 engaging the book and by engaging with the rear edge of the book push it ahead of the fingers referred to as for example as shown in Fig. 3, thereby insuring a clearance between the fingers 44 and the rear edge of the book in the movement of the fingers around the sprocket 42^b, the chain 177 delivering the wrapped books, as to an endless belt conveyor shown as comprising a series of endless belts 182 supported at their opposite ends on pulleys, the pulleys at one end being represented at 183 and secured to a shaft 184 driven by a sprocket chain 185 from a shaft 186 connected with the drive shaft 46 through the medium of meshing gears 187 and 188 on the shafts 186 and 46, respectively.

The chain 177 is driven through the medium of the shaft 174 to which the sprocket 178 is connected, the sprocket 173 being smaller than

the sprocket 172 whereby the desired surface speeds of the chains 169 and 177, for the purposes above stated, are effected.

The feature of providing the book hopper as a structure vertically adjustable relative to the conveyor 30 is of advantage not only because it permits of the machine being used for the wrapping of books of greatly varying thicknesses, but also because it permits of the engagement of the fingers 44 with the edges of the books, for feeding them, throughout substantially the entire height of such edges regardless of the thicknesses of the books.

Where the books are of such character or size that they would become distorted out of flat condition in the folding of the wrappers about them, it is desirable that means be provided at the folding devices and over which the wrappers are folded to prevent the occurrence of such distortion. In Figs. 20 and 21 a modification of the machine of the preceding figures and incorporating means for the purpose just referred to, is illustrated, this modified machine being identical with the machine of the preceding figures except for the addition of means as above referred to shown as comprising two striplike metal members 189 and 190 which extend lengthwise of the machine and overlie the longitudinal edges of the books as they pass between them, these members being each supported at one end only as by brackets 191 and 192, respectively, which rise from the machine frame at points beyond the opposite longitudinal edges of the wrappers, the other ends of the members 189 and 190 being unsupported. The members 189 and 190 are flexible at their free ends in a vertical direction, viz., in a direction parallel to the folds, but relatively rigid in a horizontal direction, viz., in a direction normal to the folds.

The member 189 is thus positioned to resist lateral pressure which would be applied against the book in the wrapping of the wrapper portion 109 about the edge of the book and also in the wrapping of the marginal edge of the wrapper portion 110 around and under this edge portion 45 of the book and the member 190 serving to resist lateral force which would be directed against the book in the folding of the wrapper portion 110 about the other edge of the book by the folding means 35.

While I have illustrated and described certain particular embodiments of my invention, I do not wish to be understood as intending to limit it thereto as the invention may be embodied in other forms of structure and the constructions shown variously modified and altered without departing from the spirit of my invention.

What I claim as new, and desire to secure by Letters Patent, is:

1. In a wrapping machine, the combination of a hopper for the articles to be wrapped and having a slotted bottom, means for feeding the articles from said hopper to a wrapper beneath it, said hopper and means being relatively vertically adjustable for the purpose set forth, and means forming a slideway for the articles discharging from the hopper inclining downwardly therefrom and flexibly connected at its upper end with said hopper.

2. In a wrapping machine, the combination of a hopper for the articles to be wrapped and having a slotted bottom, means for feeding the articles from said hopper to a wrapper beneath it, said hopper and means being relatively vertically adjustable for the purpose set forth, and means

forming a slideway for the articles discharging from the hopper hinged to said hopper and inclining downwardly therefrom and adjustable with said hopper.

5 3. In a wrapping machine, the combination of a hopper for the articles to be wrapped and having a slotted bottom, means for feeding the articles from said hopper to a wrapper beneath it, said hopper and means being relatively vertically adjustable for the purpose set forth, a slideway for the articles discharging from the hopper hinged to the hopper and inclining downwardly therefrom toward said first-named means, and means supporting the lower end of said slideway in spaced relation to said first-named means.

10 4. In a wrapping machine, the combination of a hopper for the articles to be wrapped and having a slotted bottom, means for feeding the articles from said hopper to a wrapper beneath it, said hopper and means being relatively vertically adjustable for the purpose set forth, a slotted slideway for the articles discharging from the hopper hinged to the hopper and inclining downwardly therefrom toward said first-named means, and means supporting the lower end of said slideway in spaced relation to said first-named means.

15 5. In a wrapping machine, the combination of a hopper for the articles to be wrapped and having a slotted bottom, means for feeding the articles from said hopper to a wrapper beneath it, said hopper and means being relatively vertically adjustable for the purpose set forth, a slideway for the articles discharging from the hopper hinged to the edge of the bottom of the hopper and inclining downwardly toward said first-named means, and means supporting the lower end of said slideway in spaced relation to said first-named means.

20 6. In a wrapping machine, the combination of a hopper for the articles to be wrapped and having a slotted bottom, means for feeding the articles from said hopper to a wrapper beneath it, said hopper and means being relatively vertically adjustable for the purpose set forth, a slotted slideway for the articles discharging from the hopper hinged to the edge of the bottom of the hopper and inclining downwardly toward said first-named means, and means supporting the lower end of said slideway in spaced relation to said first-named means.

25 7. In a wrapping machine the combination of means for carrying the wrapper and the articles to be wrapped along the machine comprising a conveyor chain having projections thereon at intervals, means for feeding wrappers in front of said projections, means for feeding an article to each of the wrappers comprising a hopper located above said conveyor and having a slotted bottom permitting passage of said projections, said hopper being vertically adjustable relative to said conveyor, a slideway for the articles discharging from the hopper hinged to the bottom of the hopper-bottom and inclining downwardly toward said conveyor, means spacing said slideway from said conveyor, means located along the path of said conveyor for folding the wrappers about the articles and means for applying an adhesive to hold the wrappers in position on the articles.

30 8. In a wrapping machine, the combination of a conveyor comprising an endless element supported to travel around a circuit having an upper straight portion and having projections which, while traveling along said straight portion, are adapted to push wrappers and articles thereon to be wrapped, means located along said straight

portion for wrapping the wrappers around the articles, a second conveyor beyond said means and overlying said straight portion and having projections adapted to engage the rear edges of wrapped articles carried by the projections on said first-named conveyor, and means for driving said second conveyor faster than said first-named conveyor for moving the articles ahead of the projections on said first-named conveyor before the last-referred-to projections move substantially away from said straight portion.

35 9. In a wrapping machine, the combination of a conveyor comprising a chain driven around a circuit having an upper straight portion and comprising a sprocket at the end of said straight portion to reverse the motion of said conveyor, said conveyor having projections adapted to carry articles and wrappers through the machine, means for feeding wrappers in front of said projections and articles to the wrappers, means located along said straight portion of said conveyor for folding the wrappers about the articles and for applying adhesive to hold the wrappers in position, a second conveyor overlying said straight portion of said conveyor at its terminal end, and means for driving said second conveyor faster than said first conveyor, said second conveyor having downwardly extending projections adapted to engage the rear margins of the wrapped articles carried by the projections on said first conveyor and move said wrapped articles ahead of said last-referred-to projections before the latter move around said sprocket.

40 10. In a wrapping machine, the combination of means for feeding wrappers and articles thereon to be wrapped, means for folding one edge of the wrappers about one edge of the articles and across the upper faces thereof to extend beyond the opposite edge of the articles, means for applying adhesive near the edges of the wrappers which underlie the articles and adjacent the edges of the articles about which the final folds of the wrappers are to be made, and means for folding said extending edges of the wrappers around said last-referred-to edges of the articles and upwardly against the adhesive applied by said third-named means.

45 11. In a wrapping machine, the combination of a hopper for the articles to be wrapped and having a slotted bottom, means for feeding the articles from said hopper to a wrapper beneath it, said hopper and means being relatively vertically adjustable for the purpose set forth, and slideway-forming means for the articles discharging from the hopper adapted to cause the articles to travel downwardly to the wrappers beneath them in the different relative adjustments of the hopper and said first-named means, the end of said last-named means adjacent the wrapper extending at substantially the same elevation in the different adjustments of said hopper.

50 12. In a wrapping machine, the combination of a hopper for the articles to be wrapped and having a slotted bottom, means for feeding the articles from said hopper to wrappers beneath it, said hopper and means being relatively vertically adjustable for the purpose set forth, downwardly-inclined slideway-forming means for the articles discharging from the hopper adapted to cause the articles to travel thereon downwardly to the wrappers beneath them in the different relative adjustments of said hopper and first-named means, and means, permitting passage of the wrappers, for supporting the lower end of said slideway-forming means at substantially the same elevation in the different adjustments of said hopper.

- tially the same elevation in the different adjustments of said hopper.
13. In a wrapping machine, the combination of a hopper for the articles to be wrapped, and having a slotted bottom, means for feeding the articles from said hopper to wrappers beneath it, said hopper and means being relatively vertically adjustable for the purpose set forth, means forming a slideway for the articles discharging from the hopper inclining downwardly therefrom and flexibly connected at its upper end with said hopper, and means, permitting passage of the wrappers, for supporting the lower end of said slideway.
14. In a wrapping machine, the combination of a hopper for the articles to be wrapped and having a slotted bottom, means for feeding the articles from said hopper to wrappers beneath it, said hopper and means being relatively vertically adjustable for the purpose set forth, means forming a slideway for the articles discharging from the hopper hinged to said hopper and inclining downwardly therefrom and adjustable with said hopper, a conveyor for said articles and wrappers, and roller means bearing on said conveyor for supporting the lower end of said slideway.
15. In a machine of the character set forth, the combination of means for feeding a wrapper with the article thereon to be wrapped, means for folding one end of the wrapper about the article to initiate the wrap, means narrower than said article for conveying said article with initial wrap, means operating upon the margins of said article and wrapper which extend beyond said conveying means one for applying adhesive for holding the wrapper in position on said article and the other for completing the folding of said wrapper about said article, and rollers between which said extended margins of article and wrapper pass operating to roll down the joint at the adhesive for securing better adhesion.
16. In a machine of the character set forth, the combination of means for feeding a wrapper with the article thereon to be wrapped, means for folding one end of the wrapper about the article to initiate the wrap, means narrower than said article for conveying said article with initial wrap, means operating upon the margins of said article and wrapper which extend beyond said conveying means one for applying adhesive for holding the wrapper in position on said article and the other for completing the folding of said wrapper about said article, and positively driven rollers between which said extended margins of article and wrapper pass operating to roll down the joint at the adhesive for securing better adhesion.
17. In a wrapping machine, the combination of means for feeding work comprising wrappers and articles thereon to be wrapped, and an endless element mounted to travel in an endless path and located above the work and having a plurality of widely spaced contacting elements adapted to directly engage with, and produce substantially cup-like indentations in, the work at localized points thereon, for the purpose set forth.
18. In a wrapping machine, the combination of means for feeding work comprising wrappers and articles thereon to be wrapped, and an endless element mounted to travel in an endless path and located above the work and having a plurality of widely spaced elastic contacting elements adapted to directly engage with, and produce substantially cup-like indentations in, the work at localized points thereon, for the purpose set forth.

19. In a wrapping machine, the combination of means for feeding work comprising wrappers and articles thereon to be wrapped, and an endless element mounted to travel in an endless path and located above the work and having a plurality of elastic rolls adapted to directly engage with, and produce substantially cup-like indentations in, the work at localized points thereon, for the purpose set forth. 5
20. In a wrapping machine, the combination of means for feeding the work comprising wrappers and articles thereon to be wrapped, an endless element mounted to travel in an endless path and located above the work and having a plurality of widely spaced contacting elements adapted to directly engage with, and produce substantially cup-like indentations in, the work at localized points thereon, and means for driving said element in the direction of travel of said means and at substantially the same speed as 15 means. 20
21. In a wrapping machine, the combination of means for carrying work comprising wrappers and articles thereon to be wrapped, along the machine and comprising a conveyor element having lugs at intervals thereon, means for feeding wrappers in front of said lugs, means for feeding the articles to said wrappers, wrapper-folding means located along the path of said conveyor element and having a plurality of widely spaced contacting elements adapted to directly engage with, and produce substantially cup-like indentations in, the work at localized points thereon for gripping the work between said conveyor element and said travelling element during the operation of said folding means, and means for applying an adhesive to the wrappers to hold them in position when folded about the articles. 25
22. In a wrapping machine, the combination of means for feeding work comprising wrappers and articles thereon to be wrapped, and an endless element mounted to travel in an endless path and located above the work and having a plurality of widely spaced contacting elements adapted to directly engage with, and produce substantially 30 cup-like indentations in, the work at localized points thereon, for the purpose of preventing slippage of the work relative to said feeding means while they are being operated on by other mechanisms. 50
23. In a wrapping machine, the combination of wrapping means; a conveyor carrying impelling means for moving a wrapper and an object to be wrapped in overlying relation one to the other past said wrapping means; means directly contacting one side of said assembled wrapper and object at separated points and producing substantially cup-shaped indentations in the assembled wrapper and article to prevent relative movement of elements of the assembly while 55 moving on the conveyor; and means to positively drive said pressure means at the same speed as the assembly. 60
24. In a wrapping machine, the combination of means for feeding work comprising wrappers and articles thereon to be wrapped, and an endless element separate from the work feeding means mounted to travel in an endless path and located above the work and having a plurality of widely spaced contacting elements adapted to 70 directly engage with, and produce substantially cup-like indentations in, the work at localized points thereon, for the purpose set forth. 65
